OTIS F. PRESBREY, OF BROOKLYN, NEW YORK

ARTICLE HANDLING DEVICE

Application filed March 28, 1927, Serial No. 178,690. Renewed August 9, 1932.

This invention relates to improvements in article handling devices and has particular reference to portable cranes, lifting devices and the like.

5 An important object of the invention is to provide a portable crane which can swing in a full circle and which when self-propelled employs a single power unit for both the hoisting and the propelling operations.

10 Another object is to provide such a device wherein a superstructure of novel construction is mounted upon a standard commercial tractor truck, or trailer, without disturbing any of the parts of the tractor.

15 Another object is to provide such a device with a resilient mounting for the superstructure, whereby to absorb shocks and strains incident to the use of the device.

20 Another object is to provide a portable swinging crane with a turret or supporting post and bracing means therefor which renders the device exceptionally rugged yet comparatively light in weight.

25 Another object is to provide an improved lift such as is commonly known in the art as a platform loader or stacker, said improved lift being characterized by a platform which is pivoted with reference to its elevating support, and which is disposed closer to the ground than prior art lift platforms.

30 Another object is to provide a portable lift, with novel guiding means whereby to prevent swaying of the elevator during its operation, and at the same time reducing friction to a minimum.

35 Another object is to provide a tractor with a swinging crane and a rear lift, with a novel power transmission system wherein both of said hoisting mechanisms are operable by a single cable or other flexible connection.

40 Another object is to provide hoisting mechanism which will be substantially fool-proof and free from possibility of damage in the event that the mechanism is operated beyond its limits of normal movement.

45 With these and other objects in view, the invention resides in the novel details of construction, combination and arrangement of

parts hereinafter set forth, illustrated in the accompanying drawings showing a preferred embodiment of the invention, and specifically pointed out in the appended claims.

55

Figure 1 is a front elevation of a portable swinging crane embodying the invention and showing the cable rigging for permitting the full circle swing of the crane boom;

Fig. 1-a is a similar fragmentary view 60 of the outer end of the boom and associated parts omitted from Fig. 1;

Fig. 2 is a side elevation of the complete device, showing the cable rigging as employed for the operation of the rear lift; 65

view through the upper portion of the rear lift guide frame;

Fig. 18 is an enlarged rear elevation of the rear lift carriage platform and guiding means showing said platform as held in in-operative position;

Fig. 19 is a vertical transverse sectional view on line 19—19 of Fig. 18; and

Fig. 20 is a horizontal sectional view on line 20—20 of Fig. 18.

The invention has been shown in the drawings as applied to a tractor, and it is especially well adapted for use on and with the commercially well known Fordson tractor because of its ruggedness, economy in operation, and ease of handling.

The invention is not restricted to this specific application, however, but it may be employed in association with other makes 20 of tractors, as well as with trucks, trailers and the like. The illustrated tractor comprises a front axle 1 and a rear axle 2, respectively provided with rubber tired 25 wheels 4 and 4, said axles being rigidly connected together by a united transmission case 5 and engine crank case 6. Also associated with the axles and crank case is a usual water cooling radiator 7 and fuel tank 8, rearwardly of which is the steering 30 wheel 9 and operator's seat 10. At one of its sides (see Fig. 2) the tractor is provided with a power take-off mechanism 11 which supplies power to a hoisting drum or niggerhead 12 to which is secured one end 35 of a cable 13 and upon which the cable is adapted to be wound or unwound as the drum is selectively rotated. While the power take-off mechanism 11 may be of other types if desired, I prefer to employ 40 such a mechanism as is disclosed in my co-pending application for Letters Patent for power transmission mechanisms, filed October 11, 1926, Serial No. 140,845.

Briefly stated, this preferred and novel 45 power take-off mechanism is made up as a unit, and can readily be applied to a standard commercial tractor, and it is characterized by a plurality of planetary gear sets having different gear ratios, and each of 50 said gear sets being controlled by a frictional binding element through the manual manipulation of control levers 14 and 15. Said control levers 14 and 15 are conveniently placed with reference to the operator's seat 10, and they render the take-off 55 mechanism 11 capable of rotating the drum 12 in either direction, as desired. The special utility of my novel power take-off unit will readily appear as the description of 60 the present invention is read.

Mounted upon the tractor chassis is a super-structure which constitutes a support for a swinging crane turret, and guide means for a platform lift. Said super- 65 structure comprises a pair of structural steel

side rails 16 and 17 extending longitudinally of the tractor, which are connected together at their forward ends by means of angle brackets 18 to a front cross member 19 which is of sufficient length to extend side- 70 wardly beyond the front wheels 3 whereby to effectively function as a bumper. The firm connection between the side rails 16 and 17 and the front cross member 19 is augmented by diagonal braces 20, best shown in 75 Fig. 3, and all of these structural elements may be secured together as by rivets, bolts or other desired fastening means. Adjacent their rear ends the side rails 16 and 17 are respectively secured to upwardly extending 80 channel members 21 and 22 which are arranged in parallel relation to each other, and provided with inwardly extending flanges 23 and 24 forming spaced guide rails for an elevator carriage. The channel mem- 85 bers 21 and 22 are firmly united together by a lower cross plate 25 and an upper cross channel 26. Between said members 25 and 26 said channel members are further connected by a longer cross channel 27 which is 90 preferably of the same length as the front cross member 19 and disposed slightly above the side rails 16 and 17, and between said channel 27 and the upper cross channel 26 is a steel angle member 28 (Figs. 2 and 9). 95 The cross channel 27 is preferably connected to the upright channels 21 and 22 by angle brackets 29 and rivets or the like 30, and the steel angle 28 may be similarly connected to said channels 21 and 22 by angle brackets 31, and rivets or bolts, as desired.

This superstructure is firmly connected to the axles of the tractor chassis in such a manner that there will be a slight degree of resiliency whereby to eliminate ill effects 105 from torsional strains incident to the use of the device. For this anchorage the side rails 16 and 17 have secured to them in the proximity of the rear axle 2, a pair of anchoring brackets 34 and 35 which are disposed at 110 opposite sides of the longitudinal center of the tractor, said anchoring brackets being alike in all respects except that one is right hand and the other left hand. As best shown in Figs. 3, 7 and 8, each of these anchoring 115 brackets has a relatively flat body portion 36 secured to the web of the corresponding side rail, as by rivets 37, and having a laterally extending portion 38 which firmly seats against the lower flange of the side rail, said portion 38 extending downwardly and formed with a semicircular bearing portion 39 adapted to rest upon the housing of the rear axle. Anchoring caps 40 are firmly maintained in opposition to the bearing portions 39 by means of cap screws 41, and the arrangement is such that the superstructure when so connected will be capable of slight rotation about the axis of the rear axle 2. Extending upwardly from the body por- 120 125 130

tions 36 of the anchoring brackets 34 and 35 are diverging arms 42 and 43, and secured to said arms 42 by rivets or otherwise are upwardly and rearwardly extending angular 5 braces 44 which have their upper ends secured to the webs of the respective lift rails 21 and 22. The functions of the arms 43 will be set forth hereinafter.

Rearwardly with respect to the front cross 10 member 19, the side rails 16 and 17 are secured together by means of a substantially U-shaped bracket 45 which is best shown in Figs. 3, 5 and 6. Said bracket 45 depends below the side rails 16 and 17, and is connected approximately at its center by means 15 of a bolt 46 with one of a pair of spaced ears 47 integrally formed adjacent the front end of the crank case 6. The central portion of the front axle 1 is engaged between 20 said spaced ears 47 and the bolt or connecting pin 46 extends through both of said ears and the axle, as well as through the bracket 45 in the direction of the longitudinal center of the tractor. In addition to this connection 25 of the superstructure to the front axle 1, a cross brace 48 extends transversely between the side rails 16 and 17 above said front axle, said brace having a bearing portion 49 which is adapted to engage against 30 a shoulder 50 on the crank case 6, and thus insure the device against accidental breakage or dislocation of parts. At its opposite ends the cross brace 48 is provided with flanges 51, and between said flanges and the webs 35 of the respective side rails 16 and 17, are secured the body portions 53 of a pair of front anchoring brackets 54. Each of the brackets 54 has an upwardly extending and rearwardly inclined arm 55 extending 40 above the side rails, and has a lower flange engaging portion 56 which terminates in a downwardly and outwardly inclined socket member 57. Associated with each socket member 57 is an inverted cup 58 which receives the upper end of a coiled compression 45 spring 59, the lower end of which is similarly received in a spring cup 60 attached to the axle 1. From this it will be evident that the springs 59 at the opposite sides of 50 the frame provide sufficient resiliency to permit slight movement of the superstructure about the axis of the bolt 46, acting as shock absorbers, for which adjusting means may be provided if desired, to vary the compression 55 of the springs 59.

Disposed above the frame, in a substantially central position, is an upwardly extending turret A which includes a stationary cylindrical tube 61, secured in a turret 60 base casting 62, said casting being firmly secured to the upper ends of converging supporting legs 63 and 64. There are two of the leg members 63 formed of standard steel channels, or the like, and they have their 65 lower ends secured to the arm portions 55

of the front anchoring brackets 54. Similarly, there are two rear supporting legs 64 which have their lower ends secured to the arms 43 of the rear anchoring brackets 34. The turret base 62 includes a brake housing 65, and a sleeve 66 (Figs. 10 to 13, inclusive) said sleeve being diametrically kerfed, as at 67, to provide opposed clamping portions 68 whereby the tubular member 61 may be firmly clamped in position, and between 70 said brake housing 65 and sleeve portion 66 is an inwardly extending annular flange 69 constituting a stop for the lower end of the tubular member 61. Adjacent its lower end, the stationary turret tube 61 is provided with a counterbore 70 in which is secured a bushing 71 of bronze or other suitable anti-friction bearing material, said bushing providing a bearing for the lower end of a rotatable turret post 72, which extends upwardly through and beyond the stationary turret tube 61. Secured to the upper end of the turret tube 61 is a thrust block 73, which is also preferably of tubular formation, and including outwardly extending bifurcated lugs 74 for the securement of downwardly diverging braces 75 and 76. The braces 75 are provided at their opposite ends with right hand and left hand screw-threaded brace caps 77 and 78, which are respectively secured as by bolts 79 and 80 to the bifurcated lugs 74 of the thrust block 73, and to foot brackets 81 which are in turn secured adjacent to the opposite ends of the front cross member 19. (Figs. 2 and 3). The braces 76 are similar in all respects to the braces 75, but shorter in length and have the brace caps 77 at their upper ends similarly attached to the thrust block lugs 74, while their caps 78 are secured at 82 to foot brackets 83, which are fastened to the rear cross channel 27. It will be noted that the points of connection of the braces 75 and 76 to the turret are considerably above the connections of the supporting legs 63 and 64 to the turret base, and furthermore that the lower ends of said braces are attached to the superstructure frame at points substantial distances outwardly from the points of connections of said supporting legs to the frame. From this it will be clear that the turret is very rigidly supported with reference to the structural steel frame previously described. By way of further bracing these members, however, I may employ a pair of substantially horizontal angle iron braces 84 which are connected at their inner ends by means of a plate 85 to the thrust block 73, and said braces diverging therefrom for connection adjacent their outer ends with a cross bar 86 of the rear lift frame. I may also provide steel angle braces 87 extending horizontally between the cross angle 28 and the turret base 62, and with these braces I prefer to associate a roof plate 88 which 130

furnishes substantial shelter for the operator in the seat 10.

The thrust block 73 is slotted as at 90 adjacent its upper end, and provided at opposite sides of said slot with apertured lugs 91 for the accommodation of a clamping bolt 92, by means of which a thrust block sleeve 93 may be secured in said thrust block. The thrust block sleeve 93 is also preferably 10 formed of bronze or the like, and has at its upper end a flange member 94 having a substantially conical thrust bearing seat 95. Intermediate its end, the rotatable turret post 72 has firmly clamped to it a bearing member 96, in the form of a sleeve which has at its lower end a flange 97, and a conical bearing surface 98 which is contra-generic to the surface 95 of the thrust block sleeve 93, and resting thereon. From this 15 it will be evident that the turret post 72 is rotatable in a full circle about its axis, and it is to be understood that either roller bearings or ball bearings may be substituted for bearings 71 and 95 if desired.

20 In order to maintain the turret post 72 in fixed position and to prevent its accidental rotation when in use, the lower end of said post extends below the annular flange 69 of the turret base, and has a brake drum 100 secured to it as by set screws 101, said brake drum being disposed within the brake housing 65. The brake drum 100 includes a cylindrical flange 102 of substantial proportions, the inner periphery of which furnishes 25 an engaging surface for friction brake bands 103 and 104 which are respectively carried by brake shoes 105 and 106 pivoted at 107 on a shelf portion 108 of a brake saddle 109. The free ends of the brake shoes 30 105 and 106 are normally forced against the inner surface of the flange 102 by a spring 110 and are connected by toggles 111 and 112 to a cam or crank 113 which is manually operable by a lever 114 to release the brake.

35 The shelf portion 108 of the brake saddle forms a closure for the brake housing 65, and has a pair of downwardly extending parallel ears 115 between which a sheave wheel 116 is rotatable on a bolt 117. The 40 cable 13 passes upwardly from the power take-off drum 12 through an opening 118 in the shelf portion 108 to which it is guided by the sheave wheel 116, and thence upwardly through the rotatable turret post 72 and 45 over another sheave 119 at the upper end of the post.

The sheave wheel 119 is rotatably mounted at 120 between the spaced vertical flanges of a pair of angle plates 121 which are secured to the end of a turret top casting 122, the body of which is in the form of a slotted sleeve clamped to the upper end of the turret post 72 by clamping bolts 123. As best 50 shown in Figs. 10 and 14, the top casting 55 122 has a pair of substantially vertical plate

portions 124 and 125 at its opposite sides, to which are detachably connected by bolts 126 a pair of boom braces 127 and 128 which, as their name implies, functions to brace a boom 129. Said boom 129 is fabricated from a plurality of structural steel elements, and preferably includes a pair of spaced parallel side channels 130 and 131 connected together at intervals in their length by cross plates 132. The web portions 133 of the boom side channels 130 and 131 are preferably in opposition to each other and the upper and lower flanges 134 and 135 extending outwardly as clearly shown in the drawings, and said cross plates 132 are secured as by riveting to said flanges. The boom 129 is inclined upwardly in a direction away from the turret post, and has the lower ends of the side channels 130 and 131 respectively riveted to arms 136 and 137 which are pivotally secured by a bolt 138 to the rotatable bearing member 96 (Figs. 10 and 11).

Intermediate their ends the boom side channels 130 and 131 are provided with brace attaching brackets 140, portions of which extend above the channel flanges 134, and to which are respectively secured the boom braces 127 and 128, their connections being pivotal at 141, adjacent the outer ends of said boom braces. The said boom braces 127 and 128 are provided with a series of bolt holes 142 for the selective passage of the bolts 126, and it will be evident that said boom may be moved about its pivotal center 138 to 90 raise or lower the free end of the boom by adjusting said brace connections at the turret top bolts 126. Such adjustments are necessary at times where the operating head room for the device is limited, and with the present structure, said adjustments can be made very quickly, and this provision does not detract from the strength of the crane. By way of obtaining a greater range of 95 adjustments, the boom side channels 130 and 131 have their web portions 133 provided with a series of apertures 143, and the brace attaching brackets 140 are adapted to be secured by bolts 144 in any of the said apertures 143 selected.

As best shown in Fig. 2, the boom 129 carries three sheaves respectively numbered 145, 146 and 147, each of which functions as part of the cable power transmission system under normal conditions of operation. The 100 sheaves 145 and 146, however, are not always maintained in said power transmission system, as will be evident from Figs. 1 and 1-a.

The sheave wheel 147 is pivoted at 148 105 in an adjustable bracket 149, as best shown in Figs. 15 and 16, said bracket having lip portions 150 and 151 at its opposite sides adapted to extend over and rest upon the top flanges 134 of the boom side channels 130 110

and 131. Extending between said boom channels, the bracket 149 has a pair of arms 152 and 153 which are transversely apertured for the reception and support of a tube 154a, through which extends an anchoring bolt 154, which also passes through the boom channel webs, and positively maintains the sheave bracket in its desired position. The boom channel webs are also provided with a series of apertures 155, any one of which may be employed for the reception of the anchoring bolt 154, with the result that said sheave bracket and its associated sheave 147 may be selectively positioned at different distances from the supported inner end of the boom. This adjustment is sometimes desirable in lifting exceptionally heavy articles, so that the entire tractor will not lose its equilibrium.

As has previously been stated, one end of the cable 13 is secured to the drum 12, and now it is to be noted that the other end of said cable is secured as at 156 to the tube 154a of the adjustable sheave anchoring bracket 149. The cable is of sufficient length to have a suspended loop 13—a extending downwardly between said tube 153a and the sheave 147, and associated with said loop is a hoisting block 157 of any desired type, preferably carrying at its lower end a usual hook 158. When the device is to be used as a full circle swinging crane, the cable 13 passes upwardly through the turret post 72 as previously explained, over the sheave 119 and thence to the sheave 147, as shown in Fig. 1.

Counterbalancing means 159 are preferably associated with the turret in order to assist in maintaining the same in its vertical position and to relieve it of excessive strains incident to hoisting with the crane boom. Also, the counterbalancing means reduces shock on the springs 59 and the pivots 46, etc., and enables such springs and pivots to better perform their functions. Such counterbalancing means comprises a pair of lower spaced angle bars 160 and 161 which are secured as at 162 to the rotatable turret bearing member 97 and extending in opposite direction from that of the boom 129. Adjacent their outer ends said angle bars 160 and 161 are rigidly connected together by a plurality of cross bars 163 which form the bottom of a counterbalance basket 164, in which suitable weights (scrap iron, sand bags, or the like) may be placed. The counterbalance basket is further characterized by a pair of spaced upper angle bars 165 and 166, which may be connected to the lower angle bars 160 and 161 by substantially vertical braces 167. The inner ends of the angle bars 165 and 166 are secured to a double ended yoke 168 (Fig. 14) which, in turn, has its inner end secured by bolts or the like 169 to the turret top 122. Associated

with the counterbalance means is a winch bracket 170, on which is mounted a manually operable winch or capstan 171, which includes a drum 172 having secured to it, and partially wound upon it one end of a boom adjusting cable 173. Said cable passes over a sheave 174, which is rotatably secured at 175 in the turret top sheave angle 121, and thence looped around a sheave 176 and the free end of the cable secured as at 177 to a portion of the counterbalance means. The sheave 176 is carried by a pulley block 178 which is pivotally attached at 179 to a pair of united angle plates 180 which are secured as by rivets, or the like, to the upper flanges 134 of the boom side channels adjacent the outer ends thereof. In adjusting the boom 129 as previously explained, it is only necessary to remove the boom brace bolts 126 and thereafter to manually operate the winch 171 to wind or unwind the cable 173 on the drum 172 resulting in raising or lowering the boom. When the desired setting has been obtained, the brace bolts 126 can be again assembled in place, and tightened, leaving the device ready for use in the adjusted condition. By virtue of the fact that the winch 171 is mounted on the counterbalance means and bodily rotatable about the axis of the turret simultaneously with the boom, it will be evident that the adjustment for height can be effected at any time regardless of the plane in which the boom happens to be standing.

Referring now particularly to Figs. 18, 19 and 20, it will be seen that the rear lift or elevator comprises a substantially rectangular carriage 183 which is reciprocable upwardly and downwardly between the vertical guide rails 21 and 22 of the superstructure previously described. Said carriage 183 is equipped at its opposite side with upper and lower guide rollers 184 and 185, which preferably have peripheries of frustoconical formation to fit fairly between the flanges 23 and 24 of the guide rails. The rollers 184 and 185 reduce friction to a minimum and maintain the carriage 183 against displacement from its operative plane. If desired, an additional pair of guide rollers 186 and 187 may be mounted at the back of the carriage 183, said rollers being rotatable on axes perpendicular to those of the rollers 184 and 185, and being guided by flanges 188 of a central guide rail 189, which is also secured to the cross members 25, 27 and 31 of the superstructure. Said rollers 186 and 187 prevent lateral displacement of the carriage 183 and effectively eliminate end thrust on the rollers 184 and 185. Adjacent its upper end and preferably in line with its vertical center, as viewed in Fig. 18, the carriage is provided with a sheave 190, rotatably held by a bolt or pin 191 which in the illustrated embodiment also

serves to hold the roller 186 in position. Under normal operating conditions the cable 13 has a loop 13-b which passes downwardly from and between the boom sheaves 145 and 146, and said loop engages over the carriage sheave 190.

Adjacent its lower end, the carriage 183 is provided at its opposite sides with rearwardly extending bifurcated lugs 192 and 193, to which are hingedly connected, as by bolts 194, a pair of rearwardly extending heels or stop arms 195, which are preferably integral with a lift platform 196. The normal operative position of the lift platform 196 is substantially horizontal, as shown in Fig. 2, and when it is not desired for use it can be swung in against the carriage 183, as clearly shown in Fig. 19. When the platform is swung down to using position, the heels or stop arms 195 bear upwardly on the frame of the carriage so that the platform will support the load thereon. To maintain the carriage 183 and its pivoted platform 196 in inoperative position, the guide rails 21 and 22 are provided with alined apertures 197 and 198, and the side flanges 199 and 200 of the carriage 183 are similarly provided with apertures which may be alined therewith. When the carriage is brought to rest in such a position that said apertures are in alinement, a locking rod 201 is adapted to be extended through the apertures (Fig. 18) and in this condition the carriage 183 will be incapable of reciprocation. As the locking rod 201 is inserted through the apertures 197 and 198 in the manner above set forth, a pair of eye-bolts 202 are threaded thereon in a position between the lift guide rails 21 and 22, and each of said eye-bolts 202 has a threaded shank 203 of sufficient length to extend rearwardly through apertures 204 in the platform 196 when said platform is swung up against the carriage. Threaded nuts 205 co-operate with said threaded shanks 203 to maintain the platform in its inoperative position.

As best shown in Figs. 2 and 17, the upper cross channel 26 of the lift guide means has secured to it an eye-bolt 206, which carries a loose ring 207. When it is desired to operate the rear lift, the hook 158 of the hoisting block 157 is engaged in the ring 207 (Figs. 2 and 9) whereby to anchor said block, and causing its sheave 208 to be merely an idler in the power transmission system. The nuts 205 are removed from the platform anchoring eye-bolts 202, permitting said platform to assume its normal horizontal position and the rod 201 is withdrawn to free the carriage 183 from its anchorage with reference to the guide rails 21 and 22. It will be evident from this that as the winch 11 is operated to wind the cable 13 on the drum 12, the tendency will be for the down-

ward loop 13-b of the cable to become shorter, and, as a consequence, the lift carriage 183 and its associated parts will be drawn upwardly, such as to a position indicated by dotted lines C in Fig. 2. As the control levers 14 and 15 are manipulated to reverse the direction of rotation of the drum 12, the cable 13 will be unwound, and the resultant slack will be pulled into the loop 13-b by the weight of the carriage 183 resulting in downward movement of said carriage.

It will be noted that the guide rails 21 and 22 of the fabricated superstructure, extend downwardly below the center of the rear axle 2 and into close proximity with the ground line. Said guide rails, therefore, will act as stops to prevent overturning of the complete tractor, in the event that a load on the platform or suspended on the crane should prove to be too heavy for the machine. The lower ends of the guide rails 21 and 22 have no obstructions for the rollers 185 or for the carriage 183 and as a result the lower end of said carriage can go all the way to the ground line. The fact that the platform 196 is pivoted to the carriage at 194 renders the device especially well adapted for use upon rough ground, and in the event that some impediment should be on the ground below the platform, it will cause said platform to move about its pivot as the carriage continues to the ground line (see dotted lines D in Fig. 2). The platform 196 has been shown in the drawings as of substantially rectangular form and of approximately the same width as the carriage 183, but it is to be understood that the shape and size of said platform may be varied in many ways for special adaptations. Such special adaptations in some instances include means for automatically tilting, holding and ejecting or discharging the articles, such as barrels, bales, cases, etc., from the platform or its equivalent; and some forms of the invention are further characterized by having the elevator guiding means extending upwardly to and supported by the boom, in front of the tractor, instead of forming a part of a rigid frame as in the drawings. In its upward movement the carriage 183 is limited by the abutment of its upper edge with the lower side of the top cross member 26, giving a substantial range of movement, and in the specific embodiment illustrated, in connection with a Fordson tractor, the device is capable of lifting weights upward of a ton. As has previously been stated, my improved power take-off unit disclosed in the previously identified copending application is particularly desirable in the present machine, since it renders the same "fool-proof". It frequently happens that an operator's attention is diverted from the lift while it is moving in one direction or the other, and

in this case, if the drum 12 continues to rotate for a short period after the carriage 183 has reached its uppermost limit, there will be no serious consequences, since the frictional control members within the take-off housing permit slippage.

When it is desired to use the hoisting block 157 in conjunction with the boom 129, it is only necessary to anchor the carriage 183 by means of the rod 201 as previously explained, and release the hook 158 from the ring 207 so that the hoisting block 157 will be suspended by the cable loop 13-a, as shown by the dotted lines E in Fig. 2. With this arrangement of the parts, the sheave wheel 190 on the carriage 183 is merely an idler in the power transmission system and the hoisting block 157 will be raised and lowered as the cable 13 is wound or unwound on the drum 12. While the cable loop 13-b includes said sheave wheel 190 in the system, the boom 129 will be limited in its swinging movements about the axis of the turret A, and if it is desired to swing said boom in a full circle, it is only necessary to disengage said cable loop 13-b from the sheave wheel 190, and wind up the slack on the drum 12, whereupon the cable extends directly from the sheave wheel 119 to the sheave wheel 147, as illustrated in Figs. 1 and 1-a, and eliminating the sheave wheels 145, 146 and 190. As was previously pointed out, swinging of the crane about the axis of the turret can easily be accomplished while the brake lever 114 is held, to release the turret brake shoes 105 and 106 from their normal binding relation with the brake drum 100, and as soon as said brake lever is released the brake automatically takes hold again to prevent rotation of the turret post 72 and its associated parts.

This apparatus has proven itself to be a great labor saver in railroad freight yards, steamship docks, industrial plants and other environments because of its compactness and ability to operate in a relatively small space, and further, because of its high efficiency and exceptional ruggedness. The motive power of the tractor is not only sufficient to transport the crane and the lift from one place to another, but will also transport heavy loads which are being maintained by the crane or the lift. In addition to the swinging crane and rear lift herein disclosed, the tractor may be equipped with attachments for removable rotary brooms, ditch fillers, and the like, or it may be permanently fitted with such devices.

From the foregoing it will be evident that an improved article handling apparatus has been provided embodying many desirable and novel features, which constitute a substantial advance in the art. The invention is, of course, susceptible of numerous modifications in the details of construction and

arrangements of parts, and the right is herein reserved to make such changes as fall within the scope of the appended claims without departing from the spirit of the invention.

Having thus described my invention, what I claim as new is:

1. In combination with hoisting means, a plurality of lifting devices, one of which is movable in a circle about the other, and a single flexible connection constantly articulating said hoisting means with each of the lifting devices.

2. In combination with hoisting means, a plurality of lifting devices having different ranges of vertical movement and one of which is movable in a circle about the other, a flexible operative connection common to each of the lifting devices and the hoisting means, and means for operating any selected one of the lifting means independently by anchoring the other lifting means.

3. In combination with a wheeled vehicle, a hoisting crane, upwardly extending guiding means on the vehicle frame, and a lifting platform guided on such guiding means, a hoisting drum, and a single cable constituting a power transmission means from the drum to both the crane and the lifting platform, to each of which the cable is constantly connected.

4. In combination with a wheeled vehicle, a swinging crane including a hoisting block, upwardly extending guiding means on the vehicle frame, an elevator guided on the guiding means, a hoisting drum, a single and constant operative connection between the drum, the hoisting block, and the elevator, and means for anchoring either the block or the elevator to render the other operable.

5. In combination with a tractor including a power unit, a full-circle swinging crane mounted upon the tractor, said crane having a hoisting block, an elevator also associated with the tractor, a hoisting drum operable by the tractor power unit, a cable for transmitting power from the drum to the hoisting block, fixed at one end to the crane and having a loop for receiving the block, and means for detachably connecting said cable with the elevator.

6. Article handling apparatus of the character set forth, comprising a mobile support, a swinging crane carried thereby, a platform lift including a movable carriage and substantially rigid guiding means therefor also carried by the mobile support, and means including a single constantly connected cable for supplying power to the crane and the platform lift as desired.

7. In combination with a wheeled vehicle, a superstructure including upwardly extending flanged guides disposed in spaced parallel relationship, an elevator carriage reciprocable in said guides, anti-friction

rollers engaging the flanges of said guides to maintain the carriage in operative position, and a lifting platform extending outwardly from the carriage and hinged with reference thereto, the platform having rearwardly projecting heels for bearing upwardly upon the lower part of the carriage when the platform is swung down.

8. In combination with a wheeled vehicle, 10 a superstructure including upwardly extending flanged guides disposed in spaced parallel relationship, an elevator carriage reciprocable in said guides, anti-friction rollers engaging the flanges of said guides to maintain the carriage in operative position, and 15 a lifting platform extending outwardly from the carriage and hinged with reference thereto, the carriage and the guides having openings adapted to register, and a locking 20 bar adapted to extend through said openings to lock the carriage against movement, and means carried by the locking bar for securing the platform in inoperative position.

9. Portable hoisting apparatus including, 25 in combination, a vehicle having front and rear axles, a frame supported on said axles, a turret mounted above the frame, spaced parallel guides associated with said frame and in substantially upright position, bracing means connecting said guides with the turret mounting, an elevator reciprocable in said guides, an outwardly extending boom associated with the turret, a hoisting block, a source of power, and a flexible connection 30 forming a transmission system from said source of power to the elevator and the hoisting block, said flexible connection suspending the hoisting block from the boom.

OTIS F. PRESBREY.
